UNITED STATES PATENT OFFICE.

BLOM O. BRYNGELSON, OF DUNBAR, IOWA.

WASHING-MACHINE.

1,215,338.

Specification of Letters Patent. Patented Feb. 13, 1917.

Application filed September 27, 1916. Serial No. 122,410.

To all whom it may concern:

Be it known that I, BLOM O. BRYNGELSON, a citizen of the United States, residing at Dunbar, in the county of Marshall, State of Iowa, have invented a new and useful Washing-Machine; and I do hereby declare the following to be a full, clear, and exact description of the invention, such as will enable others skilled in the art to which it appertains to make and use the same.

This invention relates to an improved washing machine, and one of the objects of the invention is to provide a device of this kind in which simple, improved, efficient, and practical features of construction are involved.

One of the features of construction is to provide a washing machine receptacle having a multiplicity of rolls arranged therein vertically and consecutively annularly adjacent the inner wall of the receptacle, and designed to rotate simultaneously, each in the same direction, and one toward the other, and provided with spiral grooves, the tendency of which being to remove the dirt from the clothes as the rollers rub the clothes, and churn and agitate the suds toward the clothes.

A further feature of the construction is to provide the upper ends of the rolls with gears, there being a ring rack in mesh with said gears, to impart motion to the rolls.

A further feature of construction is the provision of a gear for imparting motion to the ring rack, and having means to hold the rack in position on the upper end of the washing machine receptacle.

In practical fields, the details of construction may necessitate alterations falling within the scope of what is claimed.

The invention comprises further features and combination of parts, as hereinafter set forth, shown in the drawings, and claimed.

In the drawings:—

- 45 Figure 1 is a view in side elevation of the improved washing machine constructed in accordance with the invention.
- 50 Fig. 2 is a vertical sectional view of the machine, on line 2—2 of Fig. 1.
- 55 Fig. 3 is a sectional view on line 3—3 of Fig. 1.
- Fig. 4 is a sectional view on line 4—4 of Fig. 2.
- 55 Fig. 5 is a plan view of the improved machine.

Fig. 6 is a detail perspective view of one of the rolls.

Fig. 7 is a detail view showing a hand crank mechanism for rotating the ring rack.

Referring more especially to the drawings, 1 designates a washing machine receptacle, which may be of any suitable shape or configuration, preferably cylindrical, and may be mounted upon any suitable legs 2. The bottom 3 of the receptacle on its interior 60 is provided with a plurality of sockets 4, to receive and constitute bearings for the pintles 5 of the vertical rolls 6, which are arranged annularly adjacent the cylindrical wall of the receptacle 1. The upper end of 65 the receptacle has an inturned annular flange 7, in bearings of which the pintles 8 of the rolls are mounted. The pintles 8 are provided with gears 9. A closure 10 engages the opening 11 of the upper end of said receptacle. The exterior of the receptacle 1 near its upper end is provided with a plurality of brackets 12. A circular ring 13 angular in cross section fits upon the upper 70 end of the receptacle 1. The inner edge of 75 the flange 14 of said ring has gear teeth 15 meshing with the teeth of the gears 9, so that when the ring 13 is rotated in one direction or the other, the gears 9 correspondingly rotate, which in turn will rotate the 80 rolls. The rolls respectively rotate in the same direction one toward the other, and by so rotating the rolls the clothes are prevented from being drawn in between the rolls. The rolls are provided with spiral grooves 85 90 16, and the grooves of every other roll extend spirally in an opposite direction to the grooves of the intermediate rolls. The ring 13 is angular in order to fit and rotate on the receptacle, as shown in Fig. 2. The exterior of the ring is provided with gear teeth 17, which are engaged by the teeth 18 of the gear 19. A bracket 20 is secured by screws 21 to the receptacle 1, and is provided with a cylindrical bearing 22, in which 100 the shaft 23 is mounted. Collars 24 are secured on the shaft 23 by the pins 25, one above and one below the bearing 22, to prevent axial movement of the shaft 23. The shaft 23 has its upper portion rectangular, 105 so that the gear 19 will rotate therewith. A pulley 26 is fitted upon the rectangular portion 27 of said shaft 23, so that any suitable power may be belted to the shaft, to rotate the gear 19. The gear 19 has an annular 110

extension flange 28, to overlie the ring 13, thereby preventing upward movement of the ring. The brackets 12 overlie the ring 13, to insure holding the same in place. A suitable 5 crank 29 is provided, and has a socket 30, to receive the upper end of the rectangular portion 27 of the shaft 23, whereby the shaft may be rotated manually, for operating the ring, which in turn will impart movement to 10 the rolls.

The invention having been set forth, what is claimed as new and useful, is:—

1. In a washing machine of the kind set forth, the combination of a cylindrical receptacle and a plurality of rolls having opposite spiral grooves and mounted vertically in bearings of the bottom of the receptacle to rotate adjacent to the interior wall of the receptacle, of gears upon the upper ends of 15 the rolls, and means mounted on the receptacle meshing with the gears respectively to impart movement to the rolls, all in the same direction.
2. In a washing machine of the kind set forth, the combination of a cylindrical receptacle and a plurality of rolls having opposite spiral grooves and mounted vertically 20

in bearings of the bottom of the receptacle to rotate adjacent to the interior wall of the receptacle, of gears upon the upper ends of 30 the rolls, and means mounted on the receptacle meshing with the gears respectively to impart movement to the rolls all in the same direction, said means comprising a circular ring angular in cross section to fit the upper end of the receptacle, brackets to support said ring and hold the same in place, one flange of the ring having teeth on its inner edge meshing with the gears respectively 35 of the rolls, said ring having exterior teeth, 40 a shaft mounted in a bearing on the exterior of the receptacle, and a gear mounted on said shaft to rotate therewith and meshing with the exterior teeth of the ring and having an annular extension flange overlying the ring 45 to prevent raising of the ring, and means for rotating said shaft.

In testimony whereof I have signed my name to this specification in the presence of two subscribing witnesses.

BLOM O. BRYNGELSON.
